UNITED STATES PATENT OFFICE.

GEORGE W. TODD, OF OMAHA, NEBRASKA.

DENTAL BRIDGE.

1,228,620.

Specification of Letters Patent. Patented June 5, 1917.

Application filed April 7, 1917. Serial No. 160,340.

To all whom it may concern:

Be it known that I, GEORGE W. Todd, a citizen of the United States, residing at Omaha, in the county of Douglas and State 5 of Nebraska, have invented certain new and useful Improvements in Dental Bridges, of which the following is a specification.

This invention relates to an improvement in dental bridges and has for its principal 10 object to provide porcelain teeth for bridges, each tooth having its posterior side provided with depressions of such form that the tooth will not be broken by stresses directed thereto. Another object is to provide 15 porcelain teeth having their posterior sides of such form that the metallic parts will provide a stronger bridge than usual. Still another object is to provide porcelain teeth for bridges having depressions of such form 20 that the teeth will be more convenient than ordinary when connecting them with the metallic parts, and to provide teeth of such form that a broken tooth may be readily replaced in a bridge without removing the 25 bridge. While the invention is illustrated in connection with dental bridges, the construction is adapted for use in connection with plate work.

With the foregoing objects in view, the 30 invention presents a novel construction, combination and arrangement of parts as described herein and claimed, and as illustrated in the accompanying drawing, where- in,

Figure 1 is a rear view and Fig. 2 is a front view of a porcelain tooth. Fig. 3 is a side view of the same. Fig. 4 is a transverse section on line 4—4 of Fig. 3. Fig. 5 is a plan view of a bridge. Fig. 6 is a rear view 35 of the teeth and crowns shown in Fig. 5 arranged for a bridge but not connected. Fig. 7 is a rear view of the bridge shown in Fig. 5. Fig. 8 is a section through the bridge on line 8—8 of Fig. 5. Fig. 9 is a 40 sectional view of the metallic part of the bridge on line 9—9 of Fig. 7.

Referring now to the drawing, the inner end of each tooth 9 is formed concaved between its front and back as indicated at 1, 50 and has a posterior, concaved depression 2 midway between its sides, the curvature being formed transversely and longitudinally of the tooth and extending from approximately near the top to open upon its concaved bottom. Numerals 3 indicate concaved depressions of uniform area, the cur-

vatures of these also being transversely and longitudinally of the tooth, and extending in length, from near the top to open on the concaved bottom of the tooth, and extending transversely from a point midway between its sides to open on the depression 2.

The convexed ridges 4 of the metallic part A of the bridge as best shown in Fig. 9, are provided with apertures 5 for receiving the pins 6, and these ridges as well as the convexed ridges 7 of the metallic part have a longitudinal as well as transverse curvature, and when the parts are assembled the ridges 4 will fill the depressions 2, and the ridges 7 will fill the depressions 3. And it may therefore be stated that the metallic part A, in addition to being connected with the metallic crowns 8, fills the spaces between the teeth as well as the depressions. While I have shown a single pin for each tooth, others may be used if desired and the pins may be dispensed with and cement substituted as a holding means in some instances.

On account of the construction as described, the bridge will adequately sustain stresses. It is well known that the gum tissue, on account of shrinkage, often fails to adequately support that part of a bridge between the crown teeth, and one of the objects of the present invention is to provide a metallic part of such form that the stresses directed longitudinally of the teeth will be sustained, and on account of the form of the depressions provided for the porcelain teeth, the metallic ridges which extend longitudinally of the teeth perform this function.

It will be noted that on account of the fact that the sides are formed convergent toward the bottom of the porcelain teeth, that the metallic parts between the teeth will have a greater breadth at the base or lower part of the bridge than at the upper part, to adequately resist stresses, and it will be seen that the convexed ridges 7 form a part of these comparatively broad portions, the object being to employ the least quantity of metal consistent with a strong construction.

On account of the convexed metallic parts 4 and 7 and the concaved parts 2 and 3 formed in the porcelain, liability to injury of the teeth will be reduced to a minimum, no angular projections being formed liable to fracture; and on account of the shape and arrangement of parts, if a porcelain tooth should become injured it may be readily re-

moved and be replaced by another porcelain tooth without injury to the crowns 8, or removal of the bridge.

What I claim and desire to secure by Letters Patent is,—

1. In a dental bridge, the combination with a plurality of teeth each having a concaved depression formed in its back midway between its sides and a pair of concaved depressions extending transversely from a point midway between its sides to open on the first named depression, each depression extending from near the top to open on the base and the curvatures of said depressions being formed longitudinally and transversely of the tooth, a metallic part having convexed ridges, each ridge having a longitudinal and a transverse curvature for engaging in said depressions when the parts are assembled.

2. In a dental bridge, the combination with a plurality of teeth each having a con-

caved base and having a concaved depression formed in its back midway between its sides and a pair of concaved depressions extending transversely from a point midway between its sides to open on the first named depression, each depression extending from near the top to open on the concaved base and the curvatures of said depressions being formed longitudinally and transversely of the tooth, a metallic part having convexed ridges, each ridge having a longitudinal and a transverse curvature for engaging in said depressions when the parts are assembled, and a plurality of pins engaging the teeth and the metallic part for maintaining said parts in connected relation.

In testimony whereof, I have affixed my signature in presence of two witnesses.

GEORGE W. TODD.
